GOLF CLUB

Albert Stanley Illes, Hoylake, England

Application June 26, 1930, Serial No. 464,021
In Great Britain June 2, 1930

7 Claims. (Cl. 273—66)

The present invention relates to golf clubs.

The object of the invention is to provide a golf club which in addition to its ordinary use in the playing of the game is adapted to assist in the picking up of golf balls by a player either from the green or out of a hole.

According to the present invention a golf club has an opening in the sole of the head which is capable of expansion to allow a ball to pass therethrough, and of contraction after such expansion to retain said ball above the opening.

According to another aspect of the invention, a golf club is provided in which an opening sufficiently large to accommodate a golf ball extends upwardly through the head from the sole thereof, resilient means being provided for retaining a ball in the opening and passage of the diametral plane of the ball passes the sole.

In a preferred form of construction a disc or washer of rubber or like resilient material having an opening therein of less diameter than that of a golf ball, is provided and such opening adjacent the sole of the club.

The head may be formed of two portions, an outer shell having an inwardly extending lip or flange forming the sole of the club, and an inner member adapted to secure the disc or washer against said lip.

The invention is more particularly described with reference to the accompanying drawing which shows one form of construction by way of example, and in which:—

Figure 1 is a sectional side elevation.

Figure 2 is a plan view.

As shown in the drawing, a golf club head is formed of an outer shell 1 having an inwardly extending lip or flange 2 forming the sole of the club and an inner portion 3 screw threaded into said outer portion and having a passage and opening 10 therethrough. An annular disc 4 is provided adjacent the sole between said lip 2 and the lower end of the inner portion 3.

The disc 4 is provided at its outer periphery with a beading 5 adapted for engagement with a correspondingly inclined surface 6 on the lower end of the inner portion 3, whereby the periphery of the disc is wedged outwardly against the shell 1. It will be appreciated of course, that other forms of beading could be employed for securing the disc in position. The inner portion 3 has a recess 7 formed on its inner surface for accommodation of part of the disc 4 when bent upwardly as shown in dotted lines, to allow passage through the sole of a golf ball 8. Thus when it is desired to pick up a golf ball, the sole of the club is pressed over

the top of the ball, so that the disc or washer 4 is bent upwardly to cause enlargement of the opening 9 therein, whereon the ball passes through the sole into the position shown in Figure 1, whereupon the disc 4 returns to its normal position and retains the ball within the opening 10. The club may then be lifted and the ball removed from the club head.

Holes or notches 11 may be provided in said inner portion 3 for engagement by a spanner to screw the same tightly into position.

It will be appreciated that the inner portion 3 may be adapted to slide into the outer shell 1 and secured in position by screws extending axially or radially through the club head. Variation in such modes of connection of course, would necessitate a slight alteration in the shape of the parts 1, 2 and 3. The various parts of the head may be made either of metal or of wood, and if desired, a metal head may be provided with a wooden covering 12 on the face, as shown in Figure 2.

It is preferable so to design the club head that it can be easily inserted into a hole in a golf course, and for this purpose the dimension of the head is shown in full scale in the drawing, is less than 3½ inches over all.

I declare that what I claim is:—

1. A golf ball retriever having the shape of a golf club with head and shaft, said head having an opening in the sole thereof of greater diameter than a golf ball, and including a perforated disc of resilient material mounted in said opening adjacent the sole.

2. A golf ball retriever having the shape of a golf club with head and shaft, said head having an opening in the sole thereof of greater diameter than a golf ball, an inwardly extending portion on said head projecting into said opening, a perforated disc of resilient material in said opening, and an annular member in said head for cooperating with said portion to maintain said disc in position, at least a portion of the internal diameter of said member having a greater diameter than a golf ball.

3. A golf ball retriever having the shape of a golf club with head and shaft, said head having a cavity therein with an opening through the sole of greater diameter than a golf ball and a radially inwardly projecting flange around the lower end of the opening for forming at the bottom a part of the sole and at its top a shoulder, a perforated disc of resilient material located in the cavity and an annular member attached to the

head and bearing against the disc for holding it in position.

4. A golf ball retriever having the shape of a golf club with head and shaft, said head having a cavity therein with an opening near the sole of greater diameter than a golf ball, a perforated disc of resilient material located in the cavity and having a peripheral lip, and an annular member located in the cavity and attached to the head and bearing against the disc for holding it in position, said member having a portion fitting inside the said lip whereby to hold the lip between said portion and the cavity wall.

5. A golf ball retriever comprising a shaft and a head having a ball-receiving recess opening of slightly greater diameter than a golf ball, said head having a shell with an integral flange at its sole extending into the recess and having a ball-engaging resilient ring resting against the inner surface of said flange and extending into the opening to be engaged by a ball in passing into the recess, said head including means to hold said ring against said flange.

6. A golf ball retriever comprising a head

bounded by sides, sole and crown, said head having a ball-receiving recess including an opening in the sole of slightly greater diameter than a golf ball and surrounded by head structure of annular cross-section in a plane parallel to the sole, a shaft joined to the annular structure at a point offset from the axis of said recess, and a ball-engaging resilient member mounted in said head and extending into said recess and adapted to be resiliently compressed against the head by the ball on passage of the ball into said recess.

7. A golf ball retriever comprising a shaft and a head bounded by sides, sole and crown, said head having a ball-receiving recess including an opening in the sole of slightly greater diameter than a golf ball, and a ball-engaging resilient member mounted in said head and extending into said recess and adapted to be resiliently compressed against the head by the ball on passage of the ball into said recess and to remain in said compressed condition between the ball and the head to hold the ball in said recess.

ALBERT STANLEY ILES.
